WILLIAM C. HIERING, OF NEWARK, NEW JERSEY, ASSIGNOR TO J. E. MERGOTT COMPANY, OF NEWARK, NEW JERSEY, A CORPORATION OF DELAWARE

KEY CASE

Application filed March 1, 1930. Serial No. 432,290.

This invention relates to cases for keys and the like, and more particularly to improvements in such cases by means of which the keys carried therein may be conveniently manipulated.

Heretofore, keys have been carried in cases in a manner which hampered the easy manipulation of the keys; and in cases where several keys have been carried on a single element, it has been impossible to remove certain keys independently of the other keys.

It is an object of this invention to provide a case for keys having a plurality of elements, each element being adapted to hold a plurality of keys, the keys being independently removable from the elements.

A further object is the provision of a simple and rugged key holding device, which enables free and easy manipulation of each key carried thereon.

These and other advantageous objects, which will later appear, are accomplished by the simple and practical construction and arrangement of parts hereinafter described and exhibited in the accompanying drawings, forming part hereof, and in which:

Figure 1 represents a plan view of the key carrying device.

Figure 2 represents a side view of the key carrying device.

Figure 3 represents a perspective view of a key holding element in the device.

Referring to the drawings, a case forming member 4, preferably formed from flexible leather or other suitable material, so that it may be folded, has attached thereto a metal plate 5, folded on itself and looped at 6 to provide a plurality of spaced bearings 8 for a pivot pin 7.

In the spaces between the bearings 8, the pin 7 is encircled by rings 9 integral with a pin element 10, the latter being connected with a ball 11, of a short chain of the well known ball and pin link type.

Each key holding element comprises a wire element bent to form resilient legs 12 and 13, and a double loop 14 and 15, the lowermost ball 11, of the chain being engaged between the loops and maintained in such position by a strip of metal 16 wrapped about the lower

half of loop 14 and engaging the legs 12 and 13. This arrangement provides universal movement of the wire element without affecting the ball and pin chain or its connection with the pin 7.

The lower extremities of legs 12 and 13 are provided respectively with transverse hooks 17 and 18 over which keys may be inserted. In operation, two or more keys are passed over the hooks 17 and 18 into the space between the legs 12 and 13 and the hooks are interlocked to prevent the keys from falling off.

Due to the resiliency of the legs 12 and 13, the hooks 17 and 18 will be maintained in engagement and they are released only by pressing the legs 12 and 13 inwardly towards each other.

It will be seen from the structure above described that either key may be removed from the wire member without in any way effecting the other key.

Also since the wire member has universal movement about the lowermost ball 11, and the ball and pin chain is pivotally connected to pin 7, the keys on the wire member may be manipulated with great ease and independently of each other.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:

1. In a key carrying device, a chain of the ball and pin type, a wire member having a pair of resilient legs and a loop portion engaging a ball of the chain, and a strip of metal wrapped about the loop portion and engaging the resilient legs to securely hold the loop portion on the ball.

2. In a key carrying device, a chain of the ball and pin type, a wire member having a pair of resilient legs and two adjacent loop portions engaging a ball of the chain, and

a strip of metal wrapped about the lower half of one of the looped portions and engaging the resilient legs to securely hold the ball between the loop portions.

5 This specification signed this 27th day of February, 1930.

WILLIAM C. HIERING.
